UNITED STATES PATENT OFFICE.

FRANK H. McLAIN, OF PORTLAND, MAINE, ASSIGNOR TO THE McLAIN CO., OF PORTLAND, MAINE, A CORPORATION OF MAINE.

AUTOMATIC WOOD-TURNING LATHE.

Application filed February 17, 1923. Serial No. 619,596.

To all whom it may concern:

Be it known that I, FRANK H. McLAIN, a citizen of the United States, residing at Portland, in the county of Cumberland and 5 State of Maine, have invented new and useful Improvements in Automatic Wood-Turning Lathes, of which the following is a specification.

My invention relates to new and novel 10 features incorporated in the construction of wood-turning lathes which are used in the manufacture of wooden articles of various shapes, such as handles, pill boxes, mailing cases, containers and other wooden devices 15 adapted to be produced by a turning process.

There are now on the market semi-automatic machines for doing this class of work. These machines are constructed with a lon- 20 gitudinally movable headstock carrying a solid chuck spindle, and with a stationary carriage equipped with turning and drill- 25 ing tools. In operating these machines, or lathes, a short bolt of wood, usually square in cross section, is first placed by the work- 30 man between the centering device, on the carriage, and the chuck. As the headstock is pulled along the bed of the lathe through the agency of a rack feed it forces the bolt forward past a rough-turning tool, which 35 is mounted on the carriage, and reduces the end of the bolt to a round dowel of a size sufficient to snugly fit a guide ring, usually called by wood-workers a "die", which is 40 also a fixture on the carriage. This turned end projects through and beyond the guide ring approximately the length of one of the handles or other pieces to be finished.

The finish-turning knives then act on this 45 projecting portion, complete the turning operation, and an independent cutting-off tool severs the finished piece from the remainder of the bolt. After the next cycle of the feed mechanism occurs the turning operation is 50 repeated on another short end which is fed forward past the guide ring, until finally the whole bolt is turned into finished pieces, with the exception of the butt end left in the chuck.

The fact that the spindle is running con- 55 tinuously, and at a high speed, makes the operation of placing these square bolts in the chuck attendant with considerable danger to the workman. Turning the end of the bolt to a dowel form and of just the

proper diameter to accurately fit the guide ring, upon which fit principally depends the support of the dowel during the finish-turning operation, is another difficulty encountered. If this fit happens to be too 60 tight, friction develops, with a consequent over consumption of power and the liability of burning the dowel; if too loose, chattering of the work when the cutting tool enters it, results. Then in these lathes, as each 65 individual bolt has to be placed singly in the chuck, a considerable loss of time occurs in the feeding arrangement.

In the invention herewith presented I 70 employ several, which I believe to be new and novel as well as superior, features in the construction of a wood-turning lathe de- 75 signed to handle the variety of work hereinbefore mentioned, with each operation on the stock, including the feeding of same to the chuck, effected by solely automatic means.

A detailed description will be given in the following pages of this specification of 80 all the parts embodied in my invention, but I will here point out, in a general way, a few of the characteristic features, and leave for the appended claims a more specific treatment of all that is new and novel per- 85 taining thereto.

In the first place I would call attention to the manner in which the dowels are fed into the lathe,—starting with a continuous light friction feed which brings the dowel up to the heavy friction feed mechanism, the latter intermittent in its action. Next my method of feeding the dowel through the chuck-carrying spindle by which I save considerable time in placing the dowel where it can be acted upon by the cutting tools. 95 Then by locating the cutting tools in close proximity to the chuck the work is much more rigidly held against the action of these tools than is the case where the turning is done on the dowel end projecting out from a guide ring in which the dowel may not be properly fitted. Also, in connection with the powerful frictional feed me- 100 chanism, I would mention the automatic stop action which does away with the expense and trouble of cutting a special rack for every different length of finish-turned piece being manufactured, and which can be easily and quickly adjusted to the minutest variation in length of the latter,—and 110

lastly, the designs of the roughing and finishing tool fixtures in which I have incorporated many advantageous movements,—especially the straight line cut of the roughing tool and the compound (shear and slide) cut of the finishing tool.

In the drawings accompanying this specification, Fig. 1 is a plan view of the lathe and feeding mechanism; Fig. 2 is a side elevation of the same; Fig. 3 is a longitudinal sectional view through the headstock, spindle and attached parts, taken on line 3—3, Fig. 1; Fig. 4 is a face view of the chuck-closing piston, and Fig. 5 is a side view of same; Fig. 6 is a fragmentary view of the chuck-closing piston and the piston-actuating disc, showing the helical-form faces in contact; Fig. 6^a is a face view of the piston-actuating disc, showing the arm by which it is operated; Fig. 7 is a section through the lathe bed, taken on line 7—7, Fig. 1, and shows a side elevation, partly in section, of the roughing-tool fixture, together with a full side elevation of the finishing-tool fixture; Fig. 8 is a section through a portion of the roughing-tool fixture, taken on line 8—8, Fig. 7; Fig. 9 is a sectional elevation of the (cross-wise of the fixture) finishing-tool fixture, taken on line 9—9, Fig. 7; Fig. 10 is a section through the tool holder and the top portion of the slide of the roughing-tool fixture, taken on line 10—10, Fig. 7; Fig. 11 is a section through the tool holder of the finishing-tool fixture, taken on line 11—11, Fig. 7; Fig. 12 is a horizontal section through finishing-tool fixture slide and saddle, taken on line 12—12, Fig. 9; Fig. 13 is a section through the bed, taken on line 13—13, Fig. 2, and shows the cams which actuate the roughing and finishing-tool fixtures; Fig. 14 is a section through roughing-tool fixture cam, taken on line 14—14, Fig. 13; Fig. 15 represents a plan view of the dowel feed-stop mechanism, and Fig. 16 is a side elevation of the same; Fig. 17 is an end view of that portion of the mechanism as viewed from line 17—17, Fig. 16, and Fig. 18 is that portion seen from line 18—18, Fig. 16; Fig. 19 is a side elevation of the cutting-off tool, and Fig. 20 an end elevation of the same; Fig. 21 is an end elevation of the main feed mechanism; Fig. 22 is a side elevation of the main feed mechanism; Fig. 23 is a plan view of the idle wheel and oscillating lever which carries the wheel; Fig. 24 is a sectional elevation through the tailstock and bed, taken on line 24—24, Fig. 2; Fig. 25 shows the upper portion of the tailstock, in section, and the pinion which actuates the tailstock spindle removed from its seat; Fig. 26 is a horizontal section through the bed, taken on line 26—26, Fig. 2, and shows a plan view of the tailstock spindle actuating cam and its connecting parts, and Fig. 27 is a side eleva-

tion, partly in section, of the primary, or light friction feed mechanism, section being taken on line 27—27, Fig. 2.

Similar numerals refer to similar parts throughout the several views in the drawings.

1 represents the bed of the lathe, which is supported on the legs 2, 2. 3 is a floor counter-shaft to which power from any suitable source may be supplied. Belting from the cone-pulley 4, on this counter, power is transmitted by a belt to the lathe counter-shaft 5 by and through the agency of the cone-pulley 6. A clutch 7 is provided in case the feed is required to be cut off from the lathe.

On the end of the shaft 5 is a pinion 8 meshing with a gear 9 rigidly secured to the cam-shaft 10, which latter extends beyond the bed to the feeding mechanism. Referring to Figs. 1, 2 and 27, 11 represents a column, supported on a flange 12 which is bolted to the floor. 13 is a casting slidably mounted on the column 11, and adjustable, vertically, on the same, using the nut 14 for this purpose. Rigidly secured to the top of 13 is a dowel receptacle 15, the floor of which is preferably set at a slight angle from horizontal. The receptacle has no lower side so that dowels placed therein may roll by gravity on to the spurred and grooved rolls 16. These rolls are fixed on the shafts 17 and are subject to continuous rotary movement by means of the pulleys 18, which revolve in the direction as indicated by the arrows. In the view in Fig. 27 the dowel marked "x" is being fed into the secondary feed mechanism, and as this particular dowel leaves the rolls the next dowel above, marked "y" will fall on to the rolls and be fed forward, and this operation is continued until all dowels have fed out of the receptacle for this,—the primary feed mechanism.

Secured to the end of the bed 1 is an extension to same, 19, on which is bolted a vertical bracketed member 20 (see Figs. 21 and 22). On the upper end of this member (20) is a vertically adjustable bearing 21, in which is journalled a shaft 22. Fixed to one end of this shaft (22) is a pulley 23 driven by any suitable power and designed to revolve continuously while the lathe is in operation. On the opposite end of the shaft 22 is a wheel 24 with the rim grooved to loosely fit each particular size of dowel passing through the feed mechanism. It will, of course, be understood that this wheel (24) is interchangeable with other wheels and the one whose groove fits the dowel being operated on is selected.

Placed vertically in line with the wheel 24, and beneath it, is another grooved wheel 25, which is an "idle" wheel and is mounted on a stud 26 secured to the side of the oscil-

lating lever 27. This lever (27) is fulcrumed over pin 28 fixed in the bracket 20. On the end of the lever 27, opposite the fulcrum point, is an adjusting screw 29, with a head 29', and in vertical alignment with a plunger 30, which reciprocates through the guide 31, and is actuated by the cam 32, the latter mounted on the shaft 10.

It will be observed, by referring to Fig. 22, that the wheel 24 is normally slightly out of contact with the upper side of the in-feeding dowel, but that the wheel 25 is at a considerably greater distance below the bottom side of the dowel. Now when the cam 32 turns, a very short rise, 32', on the latter, forces the plunger upward and the telescoping pin 33, impinging on the screw head 29', raises the lever 27 into a position as shown by the dot-and-dash lines, Fig. 22. Also the grooved wheel 25 is raised into contact with the dowel and in the continuation of the upward movement of the plunger 30, which has an overtravel, the wheel 25 will have pressed the dowel into a strong contact with the revolving wheel 24, which will start the dowel feeding forwardly. The cam 32 will have raised the plunger 30 more than just enough to bring the dowel into contact with the wheel 24, and this overtravel will be taken up by the telescoping of the pin 33 into the counterbored portion of the plunger, compressing the spring 34 while so doing. This excess travel of the plunger 30 allows of a strong contact of the revolving wheel 24 with the dowels and does away with the difficulty of handling large quantities of the latter where many will vary slightly (either over or under size) from the nominal size in diameter.

At 35 is seen a vertical arm pivoted on the shaft 36, which latter oscillates in the bearings 37. On the upper end of the arm 35 is an adjustable latch member 38 adapted to normally rest against the shoulder 39, on the lever 27. Tension to bring this latch member strongly against this shoulder is provided by the helical spring 40. On the completion of the upward oscillation of the lever 27 the shoulder 39 will have been raised sufficiently to have allowed the latch member to fall off the shoulder and land on the surface 41, where it temporarily remains, and so long as it remains in this position the dowel will continue to move through the feed rolls 24 and 25. It will be noticed that the surface 41 is slightly angled from horizontal. This is for the purpose of providing for slight differences in the diameters of the dowels, for the smaller the dowel the higher will the lever 27 rise, and the farther along the surface 41 will the latch member move, and without the beveled surface the latch member would not avail to hold the wheel in rigid contact with the dowel. Of course with a dowel larger than nominal size

the reverse holds true in regard to the lever and arm,—the arm will not rise so high and the latch will not move in so far.

A stud 42, on the arm 35, carries a swiveling member 43, through a hole 44 in which reciprocates a rod 45 with an adjusting nut 46 mounted on its outer end, which is threaded for a certain distance. This rod (45) which has attached thereto a spring 45' to bring it back to its normal position in the swiveling member 43, carries forward to the central part of the lathe and connects with the dowel-stop mechanism, about which more will be said later on in this specification. A spring 47 assists the lever 27 to come to its lowermost position. Guiding tubes 48 loosely support the in-feeding dowel.

Before passing from the consideration of this feed mechanism it might be well to state, what is already evident, that the feed through the two feed wheels 24 and 25 is intermittent, while the feed from the dowel receptacle is continuous in so far as the operating mechanism for this particular feed is concerned, the intermittency of the feed from the receptacle being due solely to the fact that the out-going dowel is continually in contact with the dowel immediately preceding it and which is already in the secondary feed mechanism (wheels 24 and 25), and can move no faster, and at such times only, as the latter mechanism is operating. During the halting periods of the feed the rolls 16 will have a slipping contact with the dowel they are carrying.

In Fig. 3 is illustrated the spindle with its contiguous parts assembled. 49 is the headstock base. 50 is a spindle mounted in bearings 51 and 52 properly supported in housing 53 and 54 respectively. 55 is a pulley, receiving power from any suitable source and furnishing rotary movement for the spindle, to which it is keyed.

On the forward end, or nose, of the spindle 50 is a chuck closer 56, operating within which is a collet, or as I shall hereinafter designate it, a chuck 57. A chuck tube 58, adapted to reciprocate within the spindle 50, and provided with a sliding key, or as sometimes called a "feather" 59, which prevents the chuck tube turning within the spindle, is removably secured at its inner end to the said chuck. Its outer end extends beyond the rearward end of the spindle. Secured to the housing 54 by the bolts 60 is a flanged cylindrical member 61, and operating reciprocally within which is a piston 62 having a feather 62' to prevent rotary movement within the cylinder. In direct connection with and between this piston (62) and the chuck tube (58) is a bearing 63, which, in this particular instance, is utilized as a thrusting medium. Immediately forward of the bearing 63 is a flanged collar 64, the

flanged portion of which being used to confine one end of a helical spring 65. A nut 66 secures the inner race of the bearing 63 and the collar 64 rigidly against a shoulder on the chuck tube 58. The outer race of the bearing 63 is pressed firmly into a counterbored portion of the piston 62.

Extending out from the rearward side of the piston 62 are projections 66' with faces of these projections cut to a true helix form. Rearwardly of the piston 62 is a disc 67 with projections on its inner face, as seen at 68, similar to the projections 66 on the piston 62. Securely fastened to the flange 69, of the cylinder 61, by bolts 70, is a circular plate 71 which retains the disc 67 within said cylinder. Screwed and shoudered on to the rearward end of the spindle 50 is a counterbored nut 72, within the counterbore of which is seated the opposite end of the aforesaid mentioned spring 65.

An arm 73 (see Fig. 6^a) is secured to the disc 67 by screws 74. This arm has a hole 75 through which the bolt 76 makes connection to the rod 77, which latter is reciprocated by the cam 78 in the side of which a cam path is cut. This cam is fixedly secured to the shaft 10. As arm 73 oscillates the disc 67 the helix surfaces on projections 68 impinge on the helix surfaces on projections 66' and force the piston 62 forwardly into the cylinder 61,—toward the chuck end of the spindle, and as the piston 62 is in direct connection with the chuck sleeve 58 and the chuck 57, this action will open the latter positively,—compressing the spring 65 at the same time. In the return movement of the disc the spring 65 will expand and act on the piston through the bearing 63, bringing the chuck 57 into the closer 56, with the helices on the piston following up the helices on the disc, which latter are receding on the return movement of the disc, until the chuck jaws firmly close on to the in-fed dowel.

At this stage, as the chuck can close no further, the piston remains longitudinally fixed, but the disc has yet to finish its oscillating stroke, which separates the helical surfaces on 66 and 68, (as seen in Fig. 3), and this separation provides a space which allows of considerable latitude in the diameter of the chuck opening, which in turn provides for a good firm chuck closure over slightly varying diameters of succeeding dowels. It will be apparent, therefore, that by this arrangement I obtain a positive opening and a yielding and variable closing of the chuck, which latter accomplishment eliminates the difficulty encountered in successfully chucking ordinary commercial dowels which are not furnished to true nominal size but may and are very apt to vary slightly in their diameters. It will also be seen that during the turning period, when the chuck is

closed, there can be no thrusting action on the main bearings 51 and 52, due in any way to the opening and closing mechanism.

In Fig. 3 I also illustrate how I have provided for handling dowels of different nominal sizes. The largest size of which the lathe is adapted to turn is one which will easily slide through the bore of the chuck tube 58. For smaller sizes I insert within the chuck tube a bushing, such as is seen at 79 and mount thereon centralizing collars 80, 81 and 82, placing them at intervals along the length of the tube. For holding this bushing firmly in the chuck tube I use a collar 83, made in halves, with a hubbed portion entering the bore of the tube and a flanged part extending outwardly and abutting on the end of said tube. When the nut 84 is brought up solidly against the collar 82 it will hold the interposing members 85 rigidly on the chuck tube 58. It will be noticed that the collars 80, 81 and 82 are of no larger diameter than can easily enter the chuck tube 58, consequently in inserting a bushing in the tube it may first be entered through the guide tubes 48 of the secondary feed mechanism.

The size of the bore of the chuck may also be reduced, to conform to the size of any particular bushing, by inserting split sections 85, securing the same to the chuck with screws 86.

If reference should be had to Fig. 7 there will be seen my rough-turning and finish-turning fixtures, and to Fig. 13 where their actuating mechanisms are illustrated. At 87 is shown a carriage, forming a part of the rough-turning fixture, and designed to fit slidably the "ways" of the bed of the lathe. Attached to this member (87) is an apron 88, encompassing the depth of the bed 1, and with a gib 89 and a gib screw 90 to insure accurate alignment of the carriage on the top of the V of the ways of said bed. Bosses 91 on this apron carry set screws 92 which abut on fixed bosses 93 projecting from the side of the bed and adjust the fixture in different positions longitudinally on the bed. In Fig. 13, 94 is a drum with a cam path 95 cut in the face of same and mounted on shaft 10. A roll 96, mounted rotatably on a stud in the bar 97, operates in this path and gives reciprocating movement to the said bar upon which latter, on the end opposite the roll 96, is cut a gear 120 rack. In close relation to the drum 94, and projecting out from the inner side of the bed 1, is a channel guide 97' for the bar 97. The rack on the end of the bar 97 meshes with a gear 98 loosely mounted on a pin 99. Contiguous to the gear 98 is another gear 100, also loosely mounted on the same pin (99), the latter gear (100) being in mesh with a rack cut on the lower end of a vertically reciprocating bar 101. On the upper 130

end of the bar 101 is cut another rack, at an angle of 90 degrees from that cut on the lower end and meshing with a gear 102 rotating over a pin 103 which is fixed in 5 the carriage 87.

Hung over the pin 103, and adapted to oscillate in a small arc about the same, is a saddle 104 provided with ears 105, slotted, and swinging between the upright sides of 10 the carriage 87, and having screws 105' for the purpose of locking the saddle in different angular positions on said carriage. Operating on this saddle (104), and reciprocating 15 between gibs thereon, is a slide member 106 with a rack cut on its central portion and meshing with the gear 102.

On the upper end of the slide member is a hub 107 in which oscillates a clamping pin 108. Abutting on the inner face of this hub 20 is another, somewhat similar, hub 109, forming a part of the tool carrier 110. Projecting from both sides of the hub 107 are ears 111, into which the screws 112 are tapped. These 25 screws provide adjusting means for the tool holder 110 which may oscillate over the pin 108, as is shown in dot-and-dash lines, Fig. 10,—the pin, of course, being slackened while the adjustments are being made.

113 is a sleeve revolving in a bearing in a 30 casting 114. The pin 99, extending through the bore of this sleeve is provided with a shouldered portion 115. As both of the gears 98 and 100 and the sleeve 113 are in line and shoulder to shoulder on the pin 99, tightening 35 of the nut 116 will clamp the three members rigidly together, between the nut and the shoulder 115, and the two gears will then revolve as one. Thus a connection is established 40 between the drum cam 94 and the slide 106. Should it be desired to move the carriage 87 longitudinally along the bed of the lathe the nut 116 may first be slackened,—which will have the effect of breaking the rigid connection of the two gears 98 and 45 100,—and the carriage placed in proper location,—using the screws 92 for this purpose. In moving the carriage the gear 98 will 50 simply roll along the rack on the bar 97, but will, being disconnected, impart no movement to the gear 100. The slide 106, also, may now be adjusted if it is required, as it 55 is perfectly free and independent of the actuating parts. When all adjustments have been completed, tightening of the nut 116 will bring all parts back again into functioning relation. A squared head may be formed on the pin, at 117, to facilitate steadyng the pin while tightening the nut.

In this fixture I have provided for all 60 necessary movements and adjustments for the tool or cutting knife 118. By oscillating the saddle about the pin 103 I may advance or withdraw the cutting tool into or out of the work. Vertical adjustments may be 65 made as hereinbefore stated. A rotatable

movement, to provide for axial adjustment of the cutter, is provided in the pin 108, and the whole fixture may move bodily along the bed. Attention is particularly called to the relation of the cutting tool to the feed of the 70 slide, in which I may obtain either a true radial cut, an under cut or a riding cut,—but always a straight cut,—of the cutting tool.

In Fig. 7 I also show a side elevation of my finishing-tool fixture mounted on one side 75 of the bed of the lathe. This fixture is designed, primarily, to give a tangential cut to the cutting tool. By swivelling the saddle so that the direction of the feed of the cutting tool is other than at 90 degrees from the 80 axis of the work being turned, and by putting a slight shear on the cutting edge of the cutting tool, I obtain a combined shear and slide cutting action, which is of very superior 85 advantage on straight turned work.

119 is a carriage, having a depending hub 120. Slotted arms 121 extend on both sides of the carriage and provide bearing and clamping means for the latter, adjustments along the ways of the bed being taken care 90 of by the slots in the arms. A counterbored space in the top of the carriage (see Fig. 9), at 122, receives a turned hub 123 on the under side of the saddle 124 and allows the saddle to be swivelled. A collared sleeve 125, the 95 collar portion being seated in a recess in the saddle, extends downwardly through the hub 120, and a nut 126 operating on the threaded portion of the sleeve clamps the saddle rigidly to the carriage in any position desired. 100 A slide 127, adapted to move longitudinally in the saddle through the agency of a rack 127' cut on one of its inner faces, carries the parts supporting the cutting tool. Extending upwardly from the slide is a bored hub 105 128 having an extended split ear 129, which by means of the bolt 130 securely and adjustably clamps the shank 131 of the swivel head 132. Ears 132' made integral with the swivel head carry adjusting screws 133, the 110 ends of the latter impinging on the top of the slide 127 and serving to adjust the swivel head rotatably on its shank. A hubbed portion of 132, 133, is bored, but not threaded, to fit the shank of the tool holder 134, which 115 latter it firmly clamps by means of a split ear 135 in combination with the clamp bolt 135'. A nut 136 offers means for elevating or depressing the tool holder, the shank of the latter being threaded for this purpose. 120

Meshing with the rack 127' is a gear 137 fixedly secured to the top end of a shaft 138, which oscillates in the sleeve 125. Fixed and shouldered on the shaft 138 is a collar 139, and in close contact with the latter is 125 a gear 140 loosely mounted on the shaft. On the opposite side of the gear (140) is another collar 141 and abutting on this latter is a nut 142. The extreme lower end of the shaft oscillates in the bearing 143. 130

Again referring to Fig. 13, 144 is a drum with a cam path 145 cut thereon, and in which the rotatable roll 146 reciprocates. A bar 147, to which the roll 146 is attached over a stud 148, extends forwardly to the gear 140,—the bar being guided, adjacent the drum, by a channel 147' milled in a projection on the side of the bed. Connection is made to the gear (137) through a 10 rack 149 cut on the forward end of the bar (147).

The slide adjusting feature of this finishing-tool fixture is somewhat similar to that which I have adopted on my roughing-tool fixture. By loosening the nut 142 the gear 140 may revolve freely on the shaft 138 and adjustments may be made in the position of the slide in the saddle or the position of the carriage on the bed, without 20 interference, one with the other.

In Fig. 24 I show a cross-sectional view of the tailstock spindle operating mechanism. 150 represents a cam fixedly mounted on the shaft 10. Guided in a channel 25 151 on the bed (1) is a bar 152 on which is mounted a roll 153 rotating over a stud 154, the latter secured to said bar (152). On the opposite end of the bar (152) is cut a rack 155 which actuates a gear 156. 157 represents the base of the tailstock and 157' 30 the outer spindle-housing. 158 is a cleat and 159 the bolts by which the tailstock base is secured to the bed of the lathe. 160 is the tailstock spindle slidably mounted in 35 the bushing 161 which is firmly secured in the bore of the housing 157'.

A rack 162 is fixed in a milled slot in the side of the spindle (160), the outer side extending beyond the periphery of the spindle and serving as a key reciprocating in a 40 key-way 162' cut in the bore of the bushing 161, and serving to prevent rotatable movement of the spindle 160. This rack (162) meshes with a gear 163 which is 45 slidably mounted on a vertical shaft 164 and driven by the latter through a feather 165. Extending downwardly from the base of the tailstock is a bracket 166 having on its lower end a bearing 167, the latter supporting 50 the lower end of the shaft 164. To this latter shaft (164) the gear 156 is fixedly secured. The gear 163 is extended upwardly and terminates in a knob to serve as a handle to facilitate the withdrawal of the gear 55 from its seat in the housing. A resilient locking-pin 168' is provided to resist any tendency of the gear to rise from its seat while under strain.

On the inner end of the spindle (160) may 60 be socketed a drill 168, or a centering tool; and clamped over the spindle is a fixture 169 adapted to carry tenoning or other special cutting tools. A collar 170 serves as a back stop for the spindle.

65 The forward movement of the tailstock

spindle (160) (or when the tailstock tools are operating on the material) is positive and direct from the cam which actuates same, but the return movement of the spindle is yielding and is accomplished by the 70 action of the spring 171, one end of which may be attached to the rack bar 152 and the other to any convenient point on the lathe bed.

As it may be necessary at times to move 75 the tailstock along the bed, I provide means for doing this by making a break in the direct connection from the cam to the spindle by withdrawing the gear 163 from out of contact with the rack 162 (see Fig. 25), 80 which leaves the spindle in any desired position while the tailstock is being moved. The gear 156 will roll along into another position on the rack 155,—provision being made 85 for this by cutting the rack of sufficient length to cover all requirements.

Referring to Figs. 19 and 20, which represent the cutting-off tool assembly, 172 is a cam fixed on the shaft 10. 173 is a reciprocating plunger with a stud 174 riveted to its side and a roll 176 adapted to revolve over the stud. This roll contacts with the periphery of the cam. A slot 177 in the plunger encompasses the shaft and aids in resisting the thrusting action of the roll 95 on the cam. The cam forces the tool into the work and the spring 173' returns it to its lowermost position. 178 is the main guide and is secured to the shaft 179 which is adjustably secured in the depending 100 hubbed portions of the headstock, 180 and 181. A cutter 182 is secured to the top of the plunger 173.

Reverting to a consideration of the dowel 105 stop mechanism hereinbefore briefly referred to, and observing Figs. 15, 16, 17 and 18, 183 is the dowel stop finger, fixed on a vertically positioned shaft 184 which oscillates in the bearings 185 and 186 which form a part of 110 a member 187. This member (187) is secured to a shaft 188 adjustably secured in the housings 157 and 189 of the tailstock.

The function of the arm 35 has hereinbefore been stated, but to more clearly connect the working of the dowel stop with this arm, I will repeat that the principal duty of the latter is to hold the lever 27, on which is mounted the idle wheel 25, in feeding position. This position is illustrated in Fig. 22 in dot-and-dash lines. To stop the feeding operation the arm 35 must be pulled from beneath the angled seat on the lever 27. To accomplish this is the function of the dowel stop finger 183, and its connecting parts, and the agent by which it is executed 125 is the dowel itself. As stated before, the stop 183 is subject to a slight oscillation,—receding until the back of the stop strikes the abutment 189'. When the in-feeding dowel contacts with the dowel stop finger it 130

turns the shaft 184, upon which, lower down is secured the arm 190, which is in direct connection with the swivelling member 43, through the rod 45, and when the nut 46 has reached and moved the adjacent end of the swivelling member sufficiently it will carry the arm 35 out from under the seat on the lever 27, which then drops and checks further feeding of the dowel.

10 With the dowel stop finger 183 hard against the abutment 189, and the nut 46 closely abutting on the end of the swivelling member 43, the latch member 38 should be slightly clear of the shouldered portion 39 of the lever 27, so as to absolutely insure the dropping of the latter.

15 In Fig. 16 the full lines show the dowel stop parts in their lowest position. This will allow the drill or other cutting tools mounted on the tailstock spindle to have a clear passage over the stop, when they are operating on the work. To raise the stop mechanism into operating position the lower end of the shaft 184 is forked, and within the forks a roll 191 is pinned, the roll traversing a cam 192 adjustably secured to the shaft 10.

20 The stop mechanism may be adjusted in and out from the tailstock by moving the shaft 188 and is designed to fulfill the requirements of a stop for any length of finished turnings within the capacity of the lathe.

25 In operation, the clutch 7 being thrown out of action, I first push a dowel, manually, from the dowel receptacle 15 through the secondary feed rolls and up to the forward end of the chuck, the former being apart and the latter open. The clutch is then thrown into operating position starting rotation of the cam shaft 10. When the cam 32 elevates the idling grooved wheel 25 so that the dowel is forced upwardly against the continuously revolving grooved wheel 24 the dowel begins to feed forwardly, and the arm 35 will have 30 passed under the lever 27, holding, temporarily, the wheel 25 in feeding position.

35 As it continues its passage through the chuck 57 the dowel will abut on the stop finger 183, which will retract slightly and in so doing draw the rod 45 and the arm 35 forwardly. This will have the effect of tripping the arm out from under the lever 27, allowing the wheels to separate and thus stop, temporarily, further feeding of the 40 dowel. At this stage the chuck operating cam 78, working in conjunction with the other chuck operating parts, will allow the chuck to close over the dowel firmly, and the drum cam 94 will start the rough turning fixture into action and on the completion of the first turning operation the finish turning tool mechanism, operated by the cam 144 performs its duty, meanwhile during both turning operations the cam 150 actuates the 45 drill or other end-cutting tool positioned in

the tailstock spindle 160. To complete the sequence of operations the cam 172 raises the cutting-off tool into contact with the attached end of the finished turned and drilled handle, severing it from the remainder of the dowel, 50 and finally, the chuck operating cam starts the mechanism which will open the chuck, and thus will have been completed one revolution of the cam shaft 10, or as I term it "one feed cycle."

55 In turning short handles from a long dowel there is always a butt-end left in the chuck, too short for a handle. If the feed was not flexible, or in other words was of a definite and constant length of time for each feed cycle, account would have to be taken of this butt-end, for added to this would also be the loss, on the forward end of the dowel following, of a piece equal in length to the difference between the length of the butt-end and that of the handle being turned.

60 In the construction of my lathe I have taken care of this difficulty. The butt-end is necessarily a loss, but from the entering end of each succeeding dowel nothing is taken off but a full length handle. To accomplish this object a mechanism capable of supplying a variable length of feed in any feed cycle is absolutely essential, although it may not be necessary to utilize it except on the last cut in each dowel. When the feed rolls are locked on a dowel they continue to feed until the forward end strikes the stop,--then they trip. The extreme length of feed possible is calculated and allowed on the cam layout to include the length of the longest dowel the lathe is capable of turning, plus a reasonable length for the butt-end.

65 For the purpose of illustration, suppose the required length of the finished handles to be 6 inches and the length of the dowel 50 inches. This would make eight handles, leaving a butt-end in the chuck of two inches,--which latter would be a loss. Now if the machine had a constant or invariable feed of 6 inches at each feed cycle, there would also be a loss of 4 inches on the forward end of the succeeding dowel, but, with a variable feed such as I employ on my lathe the 4 inches would not be a loss as the in-feeding dowel would continue to the stop 70 105 110 115 120 125 130 135 140 145 150 155 160 165 170 175 180 185 190 195 200 205 210 - with a chuck mounted on the nose of said spindle; of means for intermittently and positively opening the jaws of said chuck; means for intermittently and yieldingly closing the jaws of said chuck; the cooperation of said positive and yielding means automatically providing for a closure of said jaws on said chuck firmly on to successive dowels, of slightly varying diameters, entering said chuck through said spindle, substantially as described.
2. In a wood-turning lathe, the combination, with a bed member; a headstock; a tailstock; a hollow spindle rotatably mounted in bearings on said headstock; and a chuck mounted on the nose of said spindle; of operable means for opening the jaws of said chuck positively; operable means for closing the jaws of said chuck yieldingly; continuously revolving grooved rolls adapted to receive, support and move dowels, singly, from a dowel receptacle, and constituting a primary dowel feed mechanism; a continuously revolving grooved wheel; an idle grooved wheel; means for intermittently bringing both of said grooved wheels into contact with an interposing dowel, and constituting a secondary dowel feed mechanism; means for aligning the primary feed rolls to accurately deliver dowels into the secondary feed wheels; means for guiding said dowels from the secondary feed wheels into and through said spindle and said chuck, substantially as described.
3. In a wood-turning lathe, the combination, with a bed; a headstock; a tailstock, and a hollow rotatable chuck carrying spindle; of a continuously revolving grooved feed wheel; an idle grooved feed wheel; means for intermittently and yieldingly moving said idle grooved feed wheel so as to encompass and force an interposing dowel into strong frictional contact with said continuously revolving wheel; means for bringing the said idle grooved feed wheel and the said continuously revolving grooved feed wheel into strong frictional contact with successive, interposing dowels, of slightly varying diameters; locking means for said idle grooved feed wheel when in closest relation to said continuously revolving grooved feed wheel; means for unlocking said idle grooved feed wheel from contact with said dowel; and means for varying the duration of movement of said dowel in any desired feed cycle of the lathe, substantially as described.
4. In a wood-turning lathe, the combination, with a bed; a headstock; a tailstock; a hollow, rotatable, headstock spindle, and a chuck mounted on the nose of said spindle, of means for automatically, intermittently and positively opening the jaws of said chuck; means for yieldingly closing the jaws of said chuck controlled by said automatic and intermittent means, so that successively fed dowels passing into said chuck, through said spindle, may be held firmly within the grasp of said jaws regardless of slight variations in the diameters of said dowels; means for keeping a continuous, unbroken line of dowels feeding intermittently into said chuck; a rough-turning tool carriage mounted on said bed; a cutting-tool; a cutting-tool holder; means for reciprocating said tool-holder; means for adjusting said tool in said holder whereby a radial cut, an under cut or a riding cut for said tool may be obtained; rotatable means for said holder to provide for adjusting said tool axially in relation to the work being turned; and means whereby said carriage may be placed in different positions along the bed of the lathe without altering, diametrically, the relation of the tool to the work, substantially as described.
5. In a wood-turning lathe, the combination, with a bed; a headstock; a tailstock; a hollow, rotatable chuck-carrying spindle, of operable means mounted on said spindle for opening the jaws of a chuck, positively; operable means for closing the jaws of said chuck yieldingly; a primary dowel feed, consisting of continuously revolving grooved rolls, a receptacle for dowels and means for gravitating said dowels on to the tops of said grooved rolls; a secondary dowel feed, consisting of a continuously revolving grooved wheel, adjustable vertically, an idle grooved wheel adapted to impinge on and yieldingly force an interposing dowel into strong frictional contact with said continuously revolving grooved wheel; means for actuating said primary and said secondary dowel feeds; means for aligning said primary dowel feed with said secondary dowel feed whereby an unbroken line of dowels from the former feed mechanism may be accurately guided to the latter feed mechanism; a rough-turning tool fixture; a rough-turning tool; means for feeding said rough-turning tool in a straight line, for approximately radial, cutting action; a finish-turning tool fixture; a finish-turning tool; means for actuating said finish-turning tool so as to procure an approximate tangential action of the cutting tool; means for procuring a combined shearing and sliding action for the cutting tool; and means for adjustably positioning said rough-turning and said finish-turning fixtures along the bed of the lathe, substantially as described.
6. In a wood-turning lathe, the combination, with a bed; a headstock; a tailstock; a hollow headstock spindle; a chuck mounted on said spindle, of a frictional feed mechanism, consisting of a continuously revolving grooved wheel, adapted to contact with, and on the top side of, an in-feeding

dowel, an intermittently operating idle grooved wheel, positioned on the opposite side of the said in-feeding dowel, and at a spaced distance from same, means for bringing both of said wheels into strong frictional contact with the interposing, in-feeding dowel, means to obtain proper frictional contact of the wheels with successive in-feeding dowels where the latter are of slightly varying diameters; means for locking the feeding mechanism when in operative position; means for unlocking the feeding mechanism when in operative position; a dowel feed stop; means for adjusting the said dowel feed stop longitudinally of the bed; means for moving the dowel stop into and out of operative position; actuating means for said feeding mechanism; a rough-turning, radial cutting tool fixture; a finish-turning, tangential cutting tool fixture; a rough-turning tool; a finish-turning tool; means for actuating said rough-turning and said finish-turning tools; a tailstock spindle; means provided on said tailstock spindle for carrying end-cutting and special tools; means for actuating said tailstock spindle axially; means for rigidly positioning said tailstock along the bed of the lathe; means for disconnecting the actuating means for said tailstock spindle while making adjustments to the latter; a cutting-off tool, adapted to reciprocate in a guide adjustably secured to the said headstock; means to actuate said cutting-off tool; a single cam shaft for all actuating cams, and means for actuating said cam shaft, substantially as described.

FRANK H. McLAIN.
